BLANK-FINISHING MACHINE.

1,360,240.

Specification of Letters Patent. Patented Nov. 23, 1920.

Application filed May 2, 1916, Serial No. 94,868. Renewed May 5, 1920. Serial No. 379,180.

To all whom it may concern:

Be it known that I, FRIEDERICH MÜLLER, a citizen of the United States, residing at Hartford, in the county of Hartford and State of Connecticut, have invented certain new and useful Improvements in Blank-Finishing Machines, of which the following is a specification.

This invention relates to improvements in blank finishing machines, and has for its object to provide a machine adapted to automatically and simultaneously perform multiple operations upon a "blank," such for example as facing, milling, drilling, reaming or threading operations.

In the present embodiment of the invention the machine is adapted to mill certain edges of a small link-blank and at the same time to ream therein two holes for the reception of connecting elements by means of which the link units are held in assembled relation in the chain.

In the drawings Figure 1 is a sectional side elevation of the machine;

Fig. 2 is a sectional plan view of the machine;

Fig. 3 is a rear end elevation of the machine;

Fig. 4 is a front sectional elevation of the machine;

Fig. 5 is a sectional detail view on the line 5—5, Fig. 1, looking toward the front of the machine;

Fig. 6 is a detail view of the clamp compensating connection; and

Fig. 7 is a detail view of the link-blank acted upon by the machine.

The machine is adapted to act in succession upon each of a number of blanks delivered through a chute from a suitable container. The machine in its preferred embodiment described and shown herein comprises six trains of mechanism, to wit: ejector mechanism adapted to remove each blank from the chute; blank positioning mechanism; automatic clamping mechanism adapted to clamp the blank against movement; carrier mechanism adapted to present the blank to the milling and reaming cutters; the milling and reaming mechanism; and oil jet means for ejecting chips from the reamer face backwardly thereof.

The frame of the machine comprises the upright standards A and the bed B. Rising from the standards A are two bracket supports C, upon the upper horizontal portions of which rest the chute frame D formed with a chute 1 which communicates at its top with any suitable container for the blanks. The lower wall 1^x of the chute is formed with a thickened portion d, the latter being provided with a horizontal aperture to receive the shank of a yielding detent member e which is normally pressed outward slightly beyond the mouth of the chute by means of a coil spring located within the said horizontal aperture, as shown in Fig. 1. The blanks pass downwardly through the chute from the container until the foremost blank enters the socket f of an ejector F, hereinafter described, the lower edge of the blank resting upon the beveled top of the stop e which thus temporarily holds the said blank in position for ejection into the clamp and its supporting carrier.

Slidably mounted upon the bed B is the sliding carrier 2, one side wall of the bed being undercut at 3 to receive the correspondingly formed side face of the carrier, a gib 4 affording a second undercut side wall for the opposite face of the carrier, see Figs. 3 and 4. The carrier 2 is formed with the lower threaded aperture 6 to receive the threaded shank of a roller stud 7, its roller 8 projecting within a peripheral cam slot 9 formed in the cam wheel 10, the latter being fixed upon a rotary shaft 11 journaled in the bearing bosses 12 of the machine frame. Shaft 11 at its rear end carries a worm wheel 13 formed with peripheral teeth meshing with a worm 13^x (Fig. 3) on transverse shaft 14, the latter being journaled in suitable bearing bosses 15 projecting from the machine frame. Shaft 14 may be driven from any suitable source of power, and to that end has fixed thereon a band wheel 16. The main function of the sliding carrier 2 is to properly present the blank to the action of the milling and reaming cutters, and to that end it has mounted thereon certain clamping mechanism adapted to receive, clamp, and finally release, a blank ejected from the chute 1.

The primary member of the clamping mechanism is the slide 17 supported for endwise movement upon the carrier 2 and held in position by means of the gibs 18, the latter being secured to the carrier by the screws 18*. In its retracted position (Fig. 1) the carrier is so disposed that its forward end is in alinement with the mouth of the chute 1 and slightly to the rear of the yielding stop 10 *e* which serves to hold the foremost blank against displacement from the socket *f* of ejector *F*. The lower face of the slide 17 is cut away at 19 to afford a clearance space for the presser 20, hinged at 21 upon a base 15 22 secured to the carrier 2, the said base and presser being formed with alined sockets to receive a coiled spring 23, by means of which the presser is normally held against the lower face of slide 17, but 20 slightly in advance of the slide when the latter is in retracted position. It will thus be seen from inspection of Fig. 1 that downward movement of the ejector *F* will carry the blank seated in socket *f* downwardly 25 thus acting upon the beveled top of stop *e* to force the latter backward against the action of its spring, the downward movement of the blank continuing until its lower edge meets presser 20. The said movement of the 30 ejector takes place at a time when the pins 24, hereinafter described, have been retracted out of the path of the downwardly moving blank.

The pins 24 are slidably mounted in parallel apertures formed in the slide 17, and are so operated that they advance and enter apertures in the blank prior to the upward movement of the ejector *F*, the blank thus being maintained in position. The slide 17 35 is cut away at 25 so that the pins are exposed, and at this point the pins are clamped within a block 26 provided with an upwardly projecting stud 27 which enters the cam slot 28 of a cam plate 29. Cam plate 40 29 is fixed upon a slide bar 30 formed with divergently-extending side walls to enter the dovetail channel of a bearing-member 31 supported between the bracket members *C* (Fig. 1). Slide bar 30 is connected at 32, 45 33, with the upper arm of a rock lever 34 fulcrumed at 35 upon the machine frame, and at its lower end provided with a roller stud 36 fitted within the cam slot 37 of cam wheel 10.

50 The ejector *F* is slidingly fitted between parallel guide plates 63 supported by bracket frame 65, 65* secured to the main frame of the machine. As hereinbefore pointed out, the ejector is provided with a 55 socket or countersunk seat *f*, and the top of said socket is in line with the top of the chute, as shown in Fig. 1, affording a shoulder at that point. The pressure of the blanks within the chute will move the lower-

most link into the socket *f*, so that the shoulder at the top thereof will engage the upper edge of the blank. The spring-pressed block *e* located below the chute at its delivery end will prevent the blank from moving downwardly out of position, but as the top of the 65 block is beveled it will afford no obstruction to the downward movement of the ejector and the blank carried thereby. The ejector is actuated from worm wheel 13. To this end a cam slot 66 is formed in the wheel 70 and is entered by the roller stud 67 of a rock lever 68 fulcrumed at 69 upon the machine frame and at its upper end pivotally connected at 70 with crank arm 71 on shaft 72, the latter extending longitudinally of 75 the machine and having secured thereon, at a point slightly to the rear of the plates 63, a second crank arm 73, pivotally connected by screw-stud 74 with the ejector.

When the blank is ejected from the chute 80 it slightly depresses presser 20, and the pins move forwardly entering the apertures in the blank and passing beyond into the reamer apertures in clamp block 38, the blank thus being so held that slide 17 may advance to 85 press it against the face of the clamp-block. For this purpose the slide 17 is actuated by suitable mechanism through an adjustable connection of such form that adjustment may be made to adapt the clamp for blanks 90 of different thickness. The primary actuating member for slide 17 is rock lever 39 (Fig. 1) fulcrumed at 40 between arms *g*, *g*, (see Fig. 4) of the depending portion 22 of carrier 2, the said lever 39 being forked at 100 its upper end to embrace the channeled side faces of a nut 41, the latter being fitted for slight endwise movement within a socket formed in the lower face of the slide 17, a threaded adjusting rod 42 being mounted 105 within a longitudinal aperture formed in the slide and entering a threaded aperture formed in the nut, the squared end 42* of the rod projecting rearwardly of the slide and thus in such position that the operator 110 may turn the rod and thus adjust the position of slide 17 relatively to the lever 39. Thus if the rod is turned to move the slide forwardly, the distance between the end thereof and the clamping block at the time 115 of clamping will be reduced, and vice versa.

Rock lever 39 is actuated through the following instrumentalities: The depending portion 39* of the lever is provided with a roller stud 43 which fits within the cam 120 slot 44* of a segment cam 44 fulcrumed at 45 between the arms *g*, *g*, of depending carrier extension 2*. Segment cam 44 is toothed and is engaged by the similarly toothed upper end of a rack bar 46, the latter being 125 provided with a friction roller 47 fitted within the cam slot 48 of cam wheel 10. Rack bar 46 is mounted to slide endwise

between two parallel guide arms 49 rising vertically from the base of the machine frame. The rack bar is cut away at 50 to clear shaft 11 in its two extreme positions 5 of reciprocation. It will be understood that cam 10 will so control the movements of lever 39 that slide 17 will be held motionless as the ejector moves downwardly and until the blank is seated upon presser 20 and engaged by pins 24. Thereupon, lever 39 will be actuated to move the slide forward until the link is firmly clamped between the end of the slide and block 38, the movement of the slide being commensurate with the adjustment of compensating connection 41 as required by the thickness of the blank.

The end of slide 17 and the face of block 38 are so shaped that the edges k , k , of the link K, illustrated in Fig. 7, are exposed to the action of two milling cutters when the carrier 2 is bodily moved forward through the action of cam 10. In the present embodiment of the invention the milling cutters 51 are fixed upon a shaft 52 journaled 20 in the bearing bosses 53 of a bracket frame 54, the said shaft 52 having fixed thereon a band wheel 55 through which the shaft and cutters may be rotated from any suitable source of power.

30 The clamping block 38 of carrier 2 is formed with two parallel apertures into which extend two reamers 56 secured in the socket ends 57 of two parallel rotary shafts 58 journaled in the bearing bosses 59 of a bracket M secured upon the bed B of the machine frame. Each of the shafts 58 is formed with gear teeth to engage gear wheel 60 on shaft 61 also journaled in bosses 59 of bracket M and having fixed thereon at its 40 outer end a band wheel N through which the reamers may be driven from any suitable source of power.

The milling cutters are vertically adjustable relatively to the machine frame, so 45 that their active positions may be changed. To this end the depending portion of the bracket frame 54 which supports the milling cutter mechanism, is formed with an angular projection 54* which is apertured 50 to receive an adjusting bolt 62, the lower portion of the latter being threaded in an aperture formed in a horizontal arm A* projecting from the side of one of the standards A. Adjusting bolt 62 is formed with 55 a squared head 62* which may be manipulated in adjusting the vertical position of the cutters.

It will be understood that it is desirable to maintain the blank in an oil bath during 60 operation of the cutters, and that the viscosity of the oil may cause the chips from the reamer to adhere to the faces of the clamping members, thus impeding a successful clamping operation, and the consequent

derangement of the machine. To avoid this, 65 means are provided for forcing the chips from the cutting edge of the reamer backwardly beyond the rear wall of clamping block 38. To this end the pins 24 are fluted for a portion of their length and a conduit 70 77 leads through the slide 17 and communicates with the fluted portions of the pins. The conduit 77 is connected with a flexible piping 78 which communicates with any suitable source of oil supply under pressure. Now, during the operation of the 75 reamers a stream of oil under pressure is propelled through the flutes in the pins, through the apertures in the blank and thence against the reamers and through the 80 flutes formed in the latter and extending back beyond the rear face of clamping block 38, the said stream of oil compelling the chips to emerge from the rear of the reamer apertures in block 38.

In the operation of the machine the continuously rotating main shaft 11 will rotate cam wheel 10 and worm wheel 13, worm wheel 13 imparting a downward movement to ejector F at a time when the 90 pins 24 are held in retracted position. When the ejected blank meets and slightly depresses presser 20, cam wheel 10 will act upon lever 34, slide bar 30, and cam plate 29, to impart a forward movement to pins 95 24, until the latter enter the apertures in the blank and pass beyond into the reamer apertures in block 38, thus maintaining the blank in position as the ejector rises, and holding the presser slightly depressed. At 100 this point, the rack bar 46 is moved downwardly and slide 17 moves forwardly to carry the blank beyond the presser and against the face of clamping block 38, the slide then being held motionless as pins 24 105 are retracted. Thereupon cam wheel 10 acts upon the carrier 2, moving the latter forwardly until the milling and reaming cutters are placed in contact with the blank, the forward movement continuing slowly 110 until the operation of the cutters is completed. When the blank has been finished, carrier 2 is retracted until the reamers are withdrawn from the blank, and thereupon slide 17 is retracted and the blank falls 115 downwardly through opening P formed in the carrier, and thence passes to a suitable receptacle. It has been found that the blank has a tendency to stick to the face of the slide as the latter is retracted, but as the 120 presser is now in normal position slightly above the lower edge of the blank, it acts to strip the blank from the slide. And if the blank sticks to the face of clamping block 38, the nose of ejector F will eject it as the 125 ejector moves a succeeding blank into clamping position.

It will be understood that various modi-

ifications may be made in the form and arrangement of the various trains of mechanism herein described, without departing from the spirit of the invention as expressed 5 in the appended claims. For example the carrier 2 may be held in fixed position and a feeding movement be imparted to the milling and reaming cutters, this being a mere reversal of the principle of operation.

10 It will also be understood that the socket *f* of the ejector and the face of the presser 20 may be so proportioned that a single blank or a plurality of blanks, may be ejected from the chute, clamped in position 15 and presented to the cutters; that the machine is operable without the use of pins 24; that the blank or blanks may be held, preliminary to the clamping thereof, between the lower face of the yielding detent 20 member and the top of the presser; that threading cutters, drills or other finishing tools may be substituted for the reamers 56 and milling cutters 51; and that any suitable means may be provided for adjusting the bracket M. In the present embodiment 25 of the machine the longitudinal adjustment of bracket M may be effected by loosening set screw S, the latter being fitted within slot 63^x formed in the bed B, and then bodily moving the bracket to the desired 30 position.

What I claim and desire to secure by Letters Patent of the United States is:—

1. In a machine of the character described, 35 a frame, a cutting tool mounted upon said frame, a second cutting tool angularly disposed relatively to the first cutting tool, means for imparting simultaneous operative movements to said tools, means including a reciprocatory clamping-holder mounted 40 upon said frame and adapted to automatically present angularly related faces of each of successive blanks to the simultaneous action of the cutters, and means for supplying 45 successful blanks to said clamping holder.

2. In a machine of the character described, 50 a frame, a cutting tool and actuating means therefor, a container adapted to hold a plurality of blanks, a damping holder for said blanks, positively acting automatic means adapted to transfer successive blanks from the container to the clamping holder, and means for causing a relative movement 55 between the clamping holder and the cutting tool.

3. In a machine of the character described, 60 a frame, a cutting tool mounted on said frame and operating means therefor, a container adapted to hold a plurality of blanks, a blank holder comprising transversely movable yielding faces, and means for automatically transferring successive blanks from the container to the said blank holder.

4. In a machine of the character described, 65 a frame, a cutting tool mounted on said frame and operating means therefor, a blank clamp comprising relatively movable faces between which the blank is held during the cutting operation, one of said faces 70 being formed with a passage for the cutting tool, and the other face being formed with a fluid passage, and means for propelling a stream of fluid through the latter passage and toward the cutting tool. 75

5. In a machine of the character described, 80 a frame, a cutting tool, a carrier mounted upon said frame and provided with a clamping face, a clamping member movable upon the carrier relatively to the clamping face, means for causing a relative movement between the carrier and the cutting tool, a container provided with a mouth, an ejector formed with a socket in register with the container mouth, and means for reciprocating 85 said ejector.

6. In a machine of the character described, 90 a frame, a cutting tool and actuating means therefor, a carrier mounted on said frame and provided with a clamping face, a clamping member movable relatively to said clamping face, a lever and an actuating member therefor, a compensating block connecting the lever with the clamping member, and means for adjusting the position of 95 said compensating block relatively to the clamping member.

7. In a machine of the character described, 100 a frame, a cutting tool and actuating means therefor, a carrier mounted on the frame, a clamping member movable with and relatively to the carrier, a container, means for transferring a blank from the container into register with the clamping member, a pin carried by the clamping member, and means 105 for retracting the pin during the active movement of the transfer means, and for thereafter projecting said pin.

8. In a machine of the character described, 110 a frame, a cutting tool and actuating means therefor, a carrier mounted on said frame, a clamping member movable with and relatively to the carrier, actuating means for said clamping member, means for causing a relative movement between the carrier and 115 said cutting tool, a pin carried by the clamping member, and means for retracting said pin when the clamping member moves into active position.

9. In a machine of the character described, 120 a frame, a cutting tool and actuating means therefor, a carrier mounted on said frame, a clamping member movable with and relatively to the carrier, a container provided with a mouth, a yielding detent member disposed below the mouth of the container, an ejector adapted to transfer a blank from the mouth of the container into register 125

with said clamping member, and a yielding presser member adapted to press the blank against the said detent member.

10. In a machine of the character described, a frame, a cutting tool and actuating means therefor, a carrier mounted on the frame, a clamping member movable with and relatively to the carrier, a container, means for transferring a blank from the container into register with the clamping member, a pin carried by the clamping member, means for retracting the pin during the active movement of the transfer means and for thereafter projecting said pin, and a yielding presser member adapted to act upon the blank transversely of the said pin.

11. In a machine of the character described, a frame, a cutting tool and actuating means therefor, a carrier mounted on said frame and provided with a clamping face formed with an aperture to receive said cutting tool, a clamping member movable relatively to said clamping face, a container, means for transferring a blank from the container into register with the clamping member, and means for causing a relative movement between the carrier and said cutting tool.

12. In a machine of the character described, a frame, a cutting tool and actuating means therefor, a carrier mounted upon the frame and provided with a clamping face, a clamping member mounted on the carrier for movement relatively to said clamping face, a lever connected to said clamping member, a toothed segment cam operatively connected to the lever, a rack bar engaging said cam, and means for reciprocating said rack bar.

13. In a machine of the character described, a frame including a bed, a cutting tool, a carrier slidably mounted on said bed, a container supported upon the frame above said carrier, a reciprocator ejector adapted to automatically transfer successive blanks from the chute to the carrier, and means for causing a relative movement between the carrier and said cutting tool.

14. In a machine of the character described, a frame including a bed, a carrier slidably mounted upon said bed, a container disposed above said bed, an ejector adapted to transfer a blank from the container to the carrier, transversely-extending shafts journaled upon the frame, said shafts adapted to support and actuate independent cutting tools, and means for causing a relative movement between the carrier and said transverse shafts.

15. In a machine of the character described, a frame, a carrier mounted upon said frame, a container disposed above the carrier, an ejector adapted to transfer a blank from the container to the carrier, a

bracket and a shaft journaled therein, a cutting tool supported upon said shaft, means for causing a relative movement between the carrier and the cutting tool, and means for vertically adjusting the said bracket upon the frame.

16. In a machine of the character described, a frame, a carrier mounted upon said frame, a container disposed above said carrier, an ejector adapted to transfer a blank from the container to the carrier, a bracket, a shaft journaled in said bracket, a cutting tool supported upon said shaft, means for causing a relative movement between the carrier and the cutting tool, and means for longitudinally adjusting said bracket upon the frame.

17. In a machine of the character described, a frame, a cutting tool mounted upon said frame, and means for imparting operative movements thereto, a container adapted to hold a plurality of apertured blanks, a clamping holder, means adapted to transfer successive blanks from the container to the clamping holder, a fluted pin carried by the clamping holder, and means for propelling a stream of fluid through the flutes of the pin and toward the cutting tool.

18. In a machine of the character described, a cutting tool, a blank carrier reciprocable relative to the cutting tool, said carrier having blank clamping means including members having opposing faces, means for causing a relative movement between said members to clamp a blank, and a pin carried by one of said members and adapted to engage a blank during said relative movement between said members.

19. In a machine of the character described, a cutting tool, a blank carrier reciprocable relative to the cutting tool, said carrier having blank clamping means including members having opposing faces, means for feeding a blank between said faces, a pin carried by one of said members and adapted to engage a blank during the relative movement between said members, and means whereby said pin is retracted during the feeding movement of a blank between said faces.

20. In a machine of the character described, a frame, a cutting tool and actuating means therefor, a carrier mounted on said frame and provided with a clamping face, a clamping member movable relatively to said clamping face, a lever and actuating means therefor, a compensating connection between said lever and the clamping member, and means for adjusting said compensating connection relatively to the clamping member.

21. In a machine of the character described, a rotary cutting tool, a blank carrier reciprocable relative to said tool, and having

an aperture into which said tool projects, said blank carrier having blank clamping means including members having opposed faces, means for causing a relative movement between said members to clamp a blank, a pin carried by one of said members and in longitudinal alinement with said aperture, and adapted to engage a blank during said relative movement between said 10 members, and means for retracting said pin

during movement of the blank carrier toward said rotary cutting tool.

In testimony whereof I have hereunto signed my name in the presence of two subscribing witnesses.

FRIEDERICH MÜLLER.
